US00D796323S

(12) **United States Design Patent** (10) **Patent No.:** **US D796,323 S**
(45) **Date of Patent:** **** Sep. 5, 2017**

(54) **COMBINED CONTAINER AND PUMP**

(71) Applicant: **The Procter & Gamble Company**,
Cincinnati, OH (US)

(72) Inventors: **Kyle William Harris**, Maineville, OH
(US); **Marek Mikovec**, Roudnice Nad
Labem (CZ); **Peter Karl Patzak**,
Muehlthal (DE)

(73) Assignee: **The Procter & Gamble Company**,
Cincinnati, OH (US)

(**) Term: **15 Years**

(21) Appl. No.: **29/587,239**

(22) Filed: **Dec. 12, 2016**

Related U.S. Application Data

(62) Division of application No. 29/545,580, filed on Nov.
13, 2015, now Pat. No. Des. 780,594.

(57) **CLAIM**

The ornamental design for a combined container and pump,
as shown and described.

DESCRIPTION

FIG. 1 is a perspective view of the container pump embodying
our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a a to plan view thereof; and,

FIG. 7 is a bottom plan view thereof.

The broken lines are included for the purpose of illustrating
the portions of the combined container and pump that form
no part of the claimed design.

1 Claim, 5 Drawing Sheets
